United States Patent Office.

ANDREW F. LAPHAM, OF NEW YORK, AND FRANK. E. PRATT, OF MOTT HAVEN, NEW YORK, ASSIGNORS TO MALCOLM C. TURNER.

Letters Patent No. 77,386, dated April 28, 1868.

IMPROVED CLOTHES-WRINGER.

The Schedule referred to in these Letters Patent and making part of the same.

TO ALL WHOM IT MAY CONCERN:

Be it known that we, ANDREW F. LAPHAM, of the city, county, and State of New York, and FRANKLIN E. PRATT, of Mott Haven, in the county of Westchester, and State of New York, have invented a new and improved Clothes-Wringer; and we do hereby declare that the following is a full, clear, and exact description thereof, reference being had to the annexed drawing forming part of this specification, in which—

Figure 1 is a front elevation of our invention.

Figure 2 is an end elevation of the same.

Similar letters of reference indicate like parts in both figures.

Our invention consists in an improved clothes-wringer, composed of four compressing-bars, held together by two swivel-links, or an equivalent therefor, said bars carrying two wringing-rollers at their forward ends, and being provided with rubber ball-springs at their rear ends, and being also provided with clamps for securing the device to the tub, as will be presently explained.

A A designate the two upper, and B B the two lower compressing-bars. Each pair of upper and lower bars, A B, are held together laterally by cross-pieces, and vertically by a swivel-link, C, one part of said link being secured to a lower bar, B, and the other part passing up through a bar, A, and at its top being provided with a screw-thread, upon which works a thumb-nut, a. A rubber spring, b, and washer, c, are interposed between the said thumb-nut and the bar A, as shown clearly in fig. 1; but we will remark that this spring and washer may be omitted, if desirable.

D D are the wringing-rollers, and they are journalled in the forward part of each compressing-bar, the journal of the lower roller being curved out sufficiently far beyond the lower bar to receive a crank, f, for operating the rollers. The position of these rollers will be understood by reference to fig. 2.

E E' are two rubber balls, one of which is arranged between the rear ends of a pair of compression-bars, A B, and, in the present instance, it is held in place by cups e e, secured to the respective bars A B.

F F are guide-pieces, placed at each end of the rollers, for properly guiding the clothes while being fed in between the rollers.

G G are two swivel-clamps, for securing the wringer to the tub. Each clamp consists of two jaws, set at a sufficient distance apart to be placed over the edge of a tub, and one of these carries a thumb-screw, d, by screwing up which the wringer is securely fastened to the tub. Each clamp is arranged so that it can be turned laterally, so as to correspond to the curve of the edge of a tub, as can be understood by reference to fig. 1.

We will here remark that should it be desired to use the same for a mangling-machine, the rollers D D can be quickly removed, and rollers suitable for mangling purposes substituted for them.

From the above description it is evident that our wringer possesses great strength, with ample provision for the yielding of the compressing-bars, and also the rollers, but its capacity for yielding is so regulated that there will be no danger of its not performing its work properly.

We are aware of a patent granted to George N. Bolles, January 24, 1865, for a wringing-machine in general appearance resembling ours, but the construction of some of the parts which enter into the combination we have shown is different from that of Bolles, to wit, the link, with its regulating thumb-screw, and the springs for compressing the forward ends of the bars. The spring in Bolles's wringer is of an entirely different construction from ours. More expense and labor are necessary, in order to make and apply it, than in ours. It possesses more parts, and is more likely to become deranged. We will further state that we distinctly disclaim anything which is shown and claimed in the said Bolles's patent.

What we claim as our invention, and desire to secure by Letters Patent, is—

A clothes-wringer, composed of the compressing-bars A B, link C, with its thumb-nut a, springs E E', and rollers D D, all constructed, arranged, and operating in the manner and for the purposes herein specified.

ANDREW F. LAPHAM,
FRANK. E. PRATT.
